UNITED STATES PATENT OFFICE

JOHN GRAHAM, OF NEW YORK, N. Y.

DESIGN FOR GIMP.

Specification forming part of Design No. **11,565**, dated December 30, 1879; application filed July 12, 1879.
[Term of patent 7 years.]

To all whom it may concern:

Be it known that I, JOHN GRAHAM, of the city, county, and State of New York, have invented a new and original Design for Gimp and other Fabrics, of which the following is a specification.

My design consists in a series of adjacent polygonal (preferably hexagonal) figures having angular zigzag outlines, and having intervening dots, and intersecting, connecting, and continuous central stripes.

The accompanying drawing represents a face view of a piece of gimp embodying my design.

A designates the body of the gimp, which may have a feathered edge, if desirable.

B designates a series of adjacent polygonal loops or figures, shown as hexagonal, having angular zigzag outlines.

C designates a series of intervening dots arranged one between the upper portions and another between the lower portions of adjacent loops or figures.

D E designate connecting and continuous stripes, shown as of different colors intersecting each other and the loops or figures B.

F designates narrow continuous stripes extending near the edges of the gimp.

The various features enumerated may be delineated in any suitable colors, and the intersecting central stripes, D and E, may either or both be composed of lesser stripes of different colors.

What I claim as new, and desire to secure by Letters Patent, is—

1. A design for gimp and other fabrics, consisting of polygonal loops or figures having angular zigzag outlines and intersecting, connecting, and continuous central stripes.

2. A design for gimp and other fabrics, consisting of polygonal loops or figures having angular zigzag outlines, intervening dots, and intersecting, connecting, and continuous central stripes.

3. A design for gimp and other fabrics, consisting of hexagonal loops or figures having angular zigzag outlines and intersecting, connecting, and continuous central stripes.

JOHN GRAHAM.
